UNITED STATES PATENT OFFICE

RALPH W. BAILEY, OF WEST NEWBURY, MASSACHUSETTS, ASSIGNOR OF
ONE-HALF TO CONRAD A. STILES, OF LOS ANGELES, CALIFORNIA.

ORDER-CARD.

No. 813,764.

Specification of Letters Patent.

Patented Feb. 27, 1906.

Application filed March 1, 1905. Serial No. 247,894.

To all whom it may concern:

Be it known that I, RALPH W. BAILEY, of West Newbury, in the county of Essex and State of Massachusetts, have invented certain new and useful Improvements in Order-Cards, of which the following is a specification.

This invention consists of a card adapted to be used in ordering household supplies in cases where it is inconvenient or impracticable to give the orders personally to the delivering agent, being particularly adapted for ordering milk and cream, for which purposes it is inserted in the neck of a milk or cream bottle; and the invention further consists in the combination of the card and such a bottle.

Of the accompanying drawings, Figure 1 represents in elevation an order - card embodying my invention. Fig. 2 represents a perspective view of a portion of a bottle with my improved order-card inserted in the neck. Figs. 3, 4, and 5 represent, respectively, an elevation, a perspective, and a sectional view of a modified form of the invention, Fig. 5 showing the device in a bottle. Fig. 6 represents a perspective view showing a bunch of the cards as they are connected together ready for use. Figs. 7 and 8 represent partial elevations of another modified form of the invention, showing the same, respectively, in and separated from a bottle.

The same reference characters indicate the same parts in all the figures.

a represents a card of comparatively stiff and elastic material, preferably of paper, which is of such thickness as to be stiff enough to cause it to remain upright when set in such a position and at the same time to be sufficiently resilient not to become broken when somewhat bent.

Intermediate its ends in the sides of the card are formed recesses *b*, which are symmetrically arranged opposite to each other. The narrowest part of the card therefore comes between the deepest portions of the recesses, and this is less than the internal diameter of the neck of a milk or cream bottle in connection with which the order-card is adapted to be used, while the end portions of the card are of greater width than the neck of the bottle, the projecting side portions of the lower end of the card constituting tongues *d*, adapted to expand after being inserted in the bottle below the contracted neck and en-

gage the sides of the bottle, thus retaining the card in an upright position and preventing it from becoming accidentally removed, as by being blown away. The diverging portions of the card at the upper limits of the recesses are adapted to rest on the lip surrounding the mouth of the bottle and support the card. In inserting the card into the bottle the lower part of the card is sprung or bowed so that the tongues *d* are brought toward each other and is then inserted into the opening of the bottle and released, whereupon the resiliency of the paper causes the tongues to spring outward into the enlarged portion of the bottle below the contracted neck and to engage with some force the sides of the bottle.

The housekeeper in using the card writes upon it the quantity of milk or cream desired and then inserts the same in the mouth of the bottle, leaving the latter where it will be found by the milkman. Preferably the cards will be printed or stamped with words indicating the character of the supplies to be delivered and with blank spaces for the insertion of the quantity required, as shown in the drawings, the words "Milk" and "Cream" being marked upon the card with spaces for writing down the number of gallons, quarts, or pints required.

The card may also be used for ordering other supplies than milk and cream and preferably will be provided with blanks for inserting the number of dozens of eggs, pounds of butter or cheese, and other household supplies.

Preferably the card is indented or perforated along the line at *c*, forming a detachable coupon *e*, upon which may be printed words and other characters similar to those upon the body of the order-card, with blanks in which duplicates of the orders written upon the body of the card may be inserted, together with a blank space for the date. This coupon may be filled out at the same time as the order-card proper and retained for future reference. In order that this may be most conveniently done, the cards are assembled together in a pack or bunch by means of staples *f* passed through them near the upper edge of each, the parts through which the staples pass being the coupon portions of the cards. Upon filling out a card and coupon with duplicate orders the card portion is detached from its coupon, leaving the coupon

attached to the remaining blank cards and also to the coupons from which the cards have been removed. By this arrangement the coupons are also kept together where 5 they may be readily found when occasion arises for referring to them. A perspective view of a bunch of order-cards stapled together is shown in Fig. 6.

Figs. 3, 4, and 5 show a card similar to 10 those shown in the other views, except that the recesses in the sides are rectangular in shape instead of being curved and are formed by bending up portions of the sides of the cards. Slits g are formed in the sides extending 15 a short distance inward from the edge and separating tongues g' from the body of the card. These tongues are then bent up at an angle to the body of the card, leaving the rectangular recesses b' in the sides. The 20 position which a card of this form occupies when placed in the bottle is shown in Fig. 5. The tongues d below the recesses spread out to engage the sides of the bottle below the contracted neck portions, and the shoulders 25 above the depressions rest on the lip about the neck of the bottle, while the tongues g' are held by the sides of the bottle-mouth at a sharp angle with the body of the card.

Another type of card is provided with only 30 one recess b^2 between the body portion a and the resilient tongue d' . The body portion below the recess in this form is of equal width with the mouth of a bottle, so that it may readily slip therein, while the recess has the 35 shape of the radial section of the lip surrounding a bottle-mouth, and the tongue d' has a projection d^2 adapted to take under such a lip after the card has been inserted in the bottle to retain the card therein.

40 I claim—

1. An order-card of material which is stiff, elastic and capable of receiving a clear pencil-mark, formed with recesses in its opposite sides intermediate its ends adapted to be inserted in the neck of a bottle in which the 45 width of the opening is less than that of the card at its ends and greater than that at the recesses.

2. An order-card formed of resilient material having a contracted intermediate portion and end portions of greater width, the card being adapted for insertion into a wide-mouthed bottle, the contracted portion adapted to reside within the contracted neck 55 and the wide portions to engage the bottle above and below the neck portion to retain the card in position.

3. An order-card of stiff, resilient paper hav-

ing a body portion formed with recesses in its sides intermediate its ends and having a detachable coupon, the body portion and coupon being provided with duplicate characters and blanks for indicating the character and quantity of the materials to be ordered. 60

4. An order-card adapted to be inserted in the mouth of a bottle, constructed of stiff, resilient paper and formed with a contracted portion adapted to occupy the contracted neck of the bottle, shoulders above said contracted portion adapted to engage and rest 70 upon the periphery of the bottle-mouth, and resilient projections or tongues below said contracted portion adapted to expand after insertion in the bottle and engage the sides of the bottle below the contracted neck portion thereof. 75

5. An order-card formed of resilient material having a contracted portion and an end portion of greater width, the card being adapted for insertion into a wide-mouthed 80 bottle, the contracted portion adapted to reside within the contracted neck and the wide portion to engage the bottle above the neck, portion to retain the card in position, the card being also provided with a locking projection. 85

6. An order-card consisting of a body portion having a recess in its side shaped to receive a portion of a bottle, and provided with an elastic locking projection and a supporting portion, and a detachable coupon connected to said body portion. 90

7. The combination with a bottle having a contracted neck, of an order-card having a narrow portion located within the mouth of the bottle, an end portion of greater width engaging and resting upon the rim of the bottle-mouth and a locking projection extending beneath a portion of the bottle for securing the card in place. 95

8. The combination with a bottle having a contracted neck, of an order-card constructed of material which is stiff, elastic and capable of receiving a mark, and formed with an intermediate part of less width than, and residing in, the mouth of the bottle, and end portions of greater width than said mouth and projecting laterally both above and below the contracted neck of the bottle. 100

In testimony whereof I have affixed my 110 signature in presence of two witnesses.

RALPH W. BAILEY.
